DESIGN FOR A GAME BOARD

Roy R. Hart, San Jose, Calif.

Application January 18, 1946, Serial No. 125,697

Term of patent 14 years

(Cl. D34—5)

To all whom it may concern:

Be it known that I, Roy R. Hart, a citizen of the United States, residing at San Jose, in the county of Santa Clara and State of California, have invented a new, original, and ornamental Design for a Game Board, of which the following is a specification, reference being had to the accompanying drawing, forming a part thereof.

I claim:

The ornamental design for a game board, as shown and described.

ROY R. HART.
